UNITED STATES PATENT OFFICE.

JAMES EDWIN HILLS, OF NEW YORK, N. Y.

DESIGN FOR A DISPLAY-CARD.

SPECIFICATION forming part of Design No. 28,713, dated May 24, 1898.

Application filed March 23, 1898. Serial No. 674,943. Term of patent 7 years.

To all whom it may concern:

Be it known that I, JAMES EDWIN HILLS, a citizen of the United States, residing at New York city, in the county of Kings and State of New York, have invented and produced a new and original Design for a Display-Card; and I do declare the following to be a full, clear, and exact description of the same, reference being had to the accompanying drawings, forming a part thereof.

My design consists in the novel configuration of a display-card such as is employed for mounting link cuff-buttons.

In the accompanying drawings, Figure 1 is a perspective view of a display-card embodying my design. Fig. 2 is a view from above.

In general appearance my design when looked at from the end presents the appearance of an inverted **V**; when looked at from the side has the appearance of an inclined parallelogram **A**, with two openings **B B** equi-

distant from the ends and near the top of the parallelogram and such openings connected with the top of the parallelogram by concaved divergent slits **C C**; when viewed from the top has the appearance of two parallelograms **A A**, inclined from each other, and such parallelograms provided with the openings **B B**, which openings communicate by means of the slits **C C**, which pass over the apex of the inclined parallelograms.

Having thus described my invention, I claim—

The design for a display-card substantially as herein shown and described. 35

In testimony whereof I affix my signature in presence of two witnesses.

JAMES EDWIN HILLS.
